SYSTEM OF ELECTRIC SIGNALING.

1,289,668.

Specification of Letters Patent.

Patented Dec. 31, 1918.

Application filed June 30, 1916. Serial No. 106,906.

To all whom it may concern:

Be it known that I, LOUIS COHEN, a citizen of the United States, residing at Washington, in the District of Columbia, have invented a certain new and useful System of Electric Signaling, of which the following is a specification.

This invention relates to an improvement in the art of signaling by electricity, particularly through means of electrical energy distributed by wires. It is designed primarily as an improvement in the art of duplex telegraphy, and is particularly adapted to cable telegraphy.

It is well known that in any system of duplex telegraphy heretofore used, a so-called artificial line is necessary. Such systems are very expensive in the equipment required, particularly when employed in long distance submarine work.

The present invention dispenses with the artificial line or cable in duplex systems of telegraphy. It also lends itself, with special advantage, to embodiment in systems designed for multiplex telegraphy.

The invention is based upon the improvement in the art of telegraphy disclosed in British Letters Patent No. 22,265 of November 9th, 1914, issued upon the invention of Lieutenant Colonel George O. Squier, U. S. Army, in which the messages are transmitted by an unbroken alternating current, the amplitude of whose waves is varied to produce the signaling impulses. The present invention employs, at the respective stations, sources of alternating current of different frequencies, so that each current becomes characteristic of the sending station at which it is produced. The invention also provides at each station, a secondary receiving circuit, which is so related to the local sending equipment and to the line that it is affected only by current from a distant station and not by the sending current of the local station. This result is accomplished by so arranging the circuits that the local sending current will be self-neutralizing in the receiving circuit, while the latter is left subject to manifestations of energy from the distant station. More specifically stated, these results are accomplished by having the local receiving circuit inductively related to the line and also to the circuit of the local sending equipment, but the inductive relation to the latter is of such character that

two currents are induced in the local receiving circuit which are of opposite phase and, therefore, seek to neutralize each other. To insure the elimination of any possible residual effects of the local transmitter, due to incomplete balance in the local receiving circuit, the latter is made to include also a loop circuit which is tuned to be in resonance with the frequency of the local sending current, and, therefore, acts in the nature of a very high resistance with respect to the local transmitting current without any effect upon the current from the distant station other than that of the actual ohmic resistance of the loop circuit.

Several methods of putting the invention into effect are herein suggested by way of illustration. For instance, the transformer element through which the receiving circuit is related to the line, may be divided or put into the form of two transformers which are in series with the line and in multiple with the local transmitter, so that the current from the latter divides itself and flows in opposite directions through them, thus setting up the aforesaid opposed currents in the receiving circuit. Or the local transmitting equipment may be arranged in an independent local circuit which is inductively related to the line and the local receiving circuit, coupled through a transformer with this local transmitting circuit, and through an independent transformer with the line; the arrangement being such that the currents induced in the receiving circuit through its respective transformers, are opposed and, therefore, tend to neutralize each other. In this arrangement, as in the arrangement previously described, a loop circuit tuned to the frequency of the local transmitting current may be employed in the receiving circuit to eliminate residual effects, and a loop circuit is preferably also employed in the local transmitting circuit and is tuned to the frequency of the distant transmitting current, in order to exclude from the local sending circuit, any energy received from the distant station and cause the latter to exert its influence wholly or mainly upon the receiving circuit. The local transmitting circuit when arranged independently and in inductive relation to the line, may be coupled directly with the receiving circuit or indirectly therewith, through the medium of an intermediate transformer circuit; the

last-named feature facilitating adjustment of phase relations between currents induced in the receiving circuit by the local transmitting current.

5 In the accompanying drawings:

Figures 1, 2 and 3 represent, schematically, three embodiments of the invention;

Fig. 1 showing each sending equipment in direct branched relation to the primary 10 of divided transformer:

Fig. 2 showing the sending equipment in direct independent local sending circuit, including the windings of two transformers by which it is coupled, respectively, with the 15 main line and the receiving circuit, while the receiving circuit has an independent transformer-connection with the main line; and

Fig. 3 showing a modification of the system 20 shown in Fig. 2, in which the receiving circuit still remains directly coupled with the grounded winding of the main circuit, but is coupled with the transmitting circuit through the medium of an intermediate 25 transformer circuit that facilitates adjustment of phase relations between the locally induced currents in the receiving circuit.

Referring to the drawings, a line or cable 1 is equipped at its respective ends with apparatus arranged according to the present 30 invention, for simultaneously sending and receiving messages. This equipment consists, according to the illustrative embodiment of Fig. 1, in the primary windings 2, 35 2^a, introduced between the cable 1 and ground connection 7^a, and forming parts of a divided transformer or two transformers whose secondary windings 3, 3^a, are included in the receiving circuit containing any suitable 40 type of receiving instrument or indicating device 10. 4 represents an adjustable resistance or any other device suitable for varying the amplitude of or otherwise affecting the sending current, for signaling. 5 is 45 a variable condenser and 5^a a variable inductance. 6 is a source of alternating current, and 7 a ground connection. These sending and receiving equipments are duplicated at the opposite end, where corresponding 50 parts bear similar reference characters, distinguished by the prime mark. The alternating current sources 6, 6', however, will be adapted to generate different frequencies, so that the output of each is characteristic 55 of its own station.

If now current is transmitted from the alternating current source 6, for instance, such current divides at the point 21 and flows partly through the primary 2 to the cable 1, and partly through the primary 2^a to ground at 7^a. Now suppose we adjust the 60 number of turns in the primaries 2 and 2^a so that the impedance of 2^a is larger than that of 2, and also establish a ratio of reactance to resistance in the primary 2^a so that

it will be equal to the ratio of reactance to resistance in the primary 2 and cable 1, a condition which can be readily realized in practice; we shall then have the greater part of the current from source 6 flowing into the cable 1 and only a small part shunted through branch 2^a to the ground at 7^a. We shall further have the currents in the two branches in phase and consequently the induced currents in the secondaries 3, 3^a, opposite in phase. By properly adjusting the coupling of the two primaries 2, 2^a, with their respective secondaries 3, 3^a, which is likewise a condition readily attainable, we shall have no current in the receiving circuit 75 3, 3^a; 10. In other words, the effect of the current from source 6 will be neutralized or balanced in this receiving circuit and the latter will be left without any manifestation of effect from the transmitting equipment, and, therefore, free to be influenced by incoming signals from the equipment at the distant end of the cable.

In order to insure absolutely against any 90 manifestation of influence of the sending current in the local receiving circuit, the latter is provided with a further safeguard in the form of a loop circuit 8, 9. If now the inductance 8 and the capacity 9 of the loop circuit are so adjusted that the relation 95 expressed by the formula $4\pi^2 N^2 LC = 1$, when N is the frequency of the current generated by alternator 6, L the inductance 8, and C the capacity 9, then the loop circuit has the same effect as that of an enormous resistance 100 introduced into the circuit, which may be of the order of 100,000 ohms or so, and as a consequence any small residual current, which would flow in the receiving secondary circuit 3, 3^a, 8, 9, 10, is completely eliminated from 105 said circuit, and the delicate receiving instrument 10 will be in no wise affected by the sending equipment. But with the arrangement as just described, current from the distant source 6', having a characteristic 110 frequency different from that of the alternator 6, flows through both primaries 2, 2^a in the same direction; the current induced in the secondaries 3, 3^a of the receiving circuit reinforce each other instead of being 115 opposed, and the effect is readily translatable into an intelligible manifestation in the receiving instrument 10. Furthermore, the loop circuit 8, 9, in the receiving circuit, having been adjusted for resonance with the 120 frequency of the source 6, is out of tune for the frequency of the current received from the source 6', even though the frequencies between these stations differ as little as 10% to 15%; hence, the loop circuit will offer no 125 greater resistance to the sum of the currents induced in the windings 3, 3^a by the distant source, than the actual ohmic resistance of the inductance coil 8.

Inductance 5^a and condenser 5 can readily 130

be adjusted so that, in combination with the inductance of coil 2 and cable 1, the minimum impedance is offered for current from the source 6, and at the same time, the impedance offered to the current frequency of the distant source 6' by the inductance 5^a and condenser 5, will be large as compared with that of the winding 2^a, so that most of the received current flowing through winding 2 will pass on to the winding 2^a with very little shunted through the local generating equipment, and thus insure the desirable conditions, already described, in the receiving circuit.

15 All the conditions described with reference to the station of alternating source 6 apply literally to the station of alternator 6'.

From the foregoing, it will be clear that 20 the current from one station has no effect upon the receiving circuit at that station; on the contrary each receiving circuit, with its delicate instrument for rendering intelligible the signals received, remains at all 25 times subject alone to the incoming signals; hence, messages can be transmitted and received over the same cable at one and the same time.

A modified system for use in practising 30 the art of duplex telegraphing as herein described, is illustrated in Fig. 2, according to which the alternating sources 6, 6' at the respective stations, which generate currents of different frequencies are in local closed 35 circuits having variable resistances 4, 4' as in Fig. 1, primaries 11, 11' with loop circuits 12, 13 and 12', 13', and primaries 14, 14'. According to this plan, the secondaries of the transformers coupled with primaries 40 11 and 14, are located at 15 and 16 at one station, while those coupled with primaries 11' and 14' are located at 15' and 16' at the other station. At the same time, the receiving circuits have independent transformer- 45 connections directly with the line, represented by windings 17, 18 at one station, and 17', 18' at the other station. The receiving secondary circuits in this installation include the loop circuits 8, 9, 8', 9', and receiving instruments 10, 10', as in Fig. 1. In 50 this arrangement, the loop circuits 8, 9 and 8', 9' are adjusted to be in resonance for the frequencies of the currents generated by sources 6 and 6', respectively. Also the 55 transformers 14, 16 and 17, 18 at a station are so adjusted that the current from source 6 induces equal and opposite currents in the receiving circuit at that station. Now, since the loop circuit 8, 9 is adjusted for resonance 60 to the frequency of the current from source 6, no perceptible current from the transmitting source 6 can flow in the local receiving circuit. At the same time, current from the distant end of the line will not 65 affect the sending circuit of source 6, be-

cause the loop circuit 12, 13 is tuned to the frequency of current from said distant end (source 6'), and, consequently, offers considerable resistance to flow of current of that frequency; hence, current from the distant 70 station passes on through the winding 17 to ground at 7, and thereby induces current in the winding 18 of the receiving circuit, unopposed by any current through transformer 14, 16, and thus affects the receiving device 10 in accordance with signals from the distant station alone. The same conditions prevail at the station of the opposite end of the cable where identical instrumentalities are employed and indicated by 80 similar reference characters distinguished by the prime mark.

Fig. 3 shows an installation similar to Fig. 2, with the modification that a third local circuit is coupled through transformer 85 14, 16 with the transmitting circuit, and through transformer 19, 20, with the circuit of receiver 10. The advantage of thus establishing induction relation between the sending and receiving circuits through the 90 medium of a third circuit, lies in the facility thereby afforded of exactly adjusting the phase relations of the currents induced in the receiving circuit, by the local sending circuit, so that said currents will neutralize 95 each other.

The general principles of the system of circuits described above, particularly if embodied as suggested in Fig. 2 or Fig. 3, may be readily extended to include multiplexing—that is sending and receiving several messages at the same time over the same line. For the case of quadruplexing, for instance, it is only necessary to have two transmitting and two receiving circuits at each end, and the frequencies of the currents generated by the alternators to be different from each other; also the circuits in regard to transformer-action and loop circuits will have to be so adjusted as 100 to exclude from each receiving circuit, not only the currents from the local transmitters, but also the current from one of the transmitters at the other end. That is, make each receiving circuit electrically opaque to 105 currents of three different frequencies, by multiplying the described system of neutralizing transformers and by introducing three loop circuits in series, each one adjusted to be in resonance with the frequencies of one of the currents to be excluded, and admit only the current of one definite 110 frequency, namely that desired to affect the receiver.

I claim:

1. A system of duplex electric signaling, without artificial line, said system comprising a line, an independent receiving circuit inductively related to the line, and a sending equipment, including a source of alter- 130

1. A system of duplex electric signaling comprising a line, two receiving circuits at the respective ends of the line, two transmitting equipments at the respective ends of the line, including sources of alternating current of different frequencies; each receiving circuit being so related, inductively, to the line as to receive maximum effect of the distant transmitting equipment but arranged to receive from the local source, two currents of same magnitude but opposite phase, so that said local receiving circuit is not affected by the local transmitter.
2. A system of duplex electric signaling comprising a line, two receiving circuits at the respective ends of the line, two transmitting equipments at the respective ends of the line, including sources of alternating current of different frequencies; each receiving circuit being so related, inductively, to the line as to receive maximum effect of the distant transmitting equipment but arranged to receive from the local source, two currents of same magnitude but opposite phase, so that said local receiving circuit is not affected by the local transmitter.
3. A system of duplex electric signaling comprising a line, two receiving circuits at the respective ends of the line, two transmitting equipments at the respective ends of the line, including sources of alternating current of different frequencies; each receiving circuit being so related, inductively, to the line as to have induced therein, two currents of opposite phase from the local transmitter, and two currents of same phase from the distant transmitter, whereby each local receiving circuit develops no manifestation from the local transmitting equipment, but maximum manifestations from the current from the distant transmitting equipment.
4. In a system of duplex electric signaling, a line, an independent receiving circuit inductively related to the line, and a sending equipment including a source of alternating current delivering its current to the transmitting circuit but inducing two currents of equal magnitude but opposite phase in, and, therefore, not affecting the receiving circuit, and said receiving circuit including a loop circuit adjusted to be in resonance with the frequency of the alternating current in the local sending equipment.
5. A system of duplex electric signaling comprising a line, two receiving circuits at the respective ends of the line, two transmitting equipments at the respective ends of the line including sources of alternating current of different frequencies; each receiving circuit being so related, inductively, to the line as to receive from the local source, two currents of same magnitude but opposite phase, and, therefore, not to be affected by the local transmitting equipment, but to receive maximum effect of the distant transmitting equipment; and each receiving circuit including a loop circuit adjusted to be in resonance with the frequency of the alternating current in the local sending equipment.
6. In a system of alternating current duplex electric signaling, a line, an independent receiving circuit inductively related to the line, and a sending equipment including a source of alternating current, delivering its current to the transmitting circuit but delivering two currents of same magnitude but opposite phase to, and, therefore, not affecting the receiving circuit; said transmitting equipment being in a local independent circuit, which also includes a loop circuit tuned to be in resonance with the frequency of current from the distant station.
7. A system of duplex electric signaling comprising a line, two receiving circuits at the respective ends of the line, two transmitting equipments at the respective ends of the line including sources of alternating current of different frequencies; each receiving circuit being so related, inductively, to the line as to receive from the local source, two currents of same magnitude but opposite phase, and therefore, not to be affected by the local transmitting equipment, but to receive maximum effect of the distant transmitting equipment; each transmitting equipment being in an independent local circuit, which also includes a loop circuit tuned to be in resonance with the frequency of the current of the distant transmitting equipment.
8. A system of duplex electric signaling comprising a line, two receiving circuits at the respective ends of the line, two transmitting equipments at the respective ends of the line, including sources of alternating current of different frequencies; each receiving circuit being so related, inductively, to the line as to receive from the local source, two currents of same magnitude but opposite phase, and, therefore, not to be affected by the local transmitting equipment, but to receive maximum effect of the distant transmitting equipment; each of said transmitting equipments being in an independent local circuit inductively related to the line; each of said local receiving circuits having transformer-connection with the local transmitting circuit, and its inductive relation to the line comprising an independent transformer-connection; the current in each local receiving circuit, induced through its two said transformer-connections, by the local transmitting circuit, being of opposite phase, and each local receiving circuit also including a loop circuit adjusted in resonance with the frequency of the local transmitting current.
9. A system of duplex electric signaling comprising a line, two receiving circuits at the respective ends of the line, two transmitting equipments at the respective ends of the line, including sources of alternating current of different frequencies; each re-

ceiving circuit being so related, inductively, to the line as to receive from the local source, two currents of same magnitude but opposite phase, and, therefore, not to be affected by the local transmitting equipment, but to receive maximum effect of the distant transmitting equipment; each of said transmitting equipments being in an independent local circuit inductively related to the line; each of said local receiving circuits having transformer-connection with the local transmitting circuit, and its inductive relation to the line comprising an independent transformer-connection; the current in each local receiving circuit, induced through its two said transformer-connections, by the local transmitting circuit, being of opposite phase; and each local transmitting circuit including a loop circuit 20 tuned to resonance with the frequency of the distant transmitting current.

10. A system of duplex electric signaling comprising a line, two receiving circuits at the respective ends of the line, two transmitting equipments at the respective ends of the line, including sources of alternating current of different frequencies; each receiving circuit being so related, inductively, to

the line as to receive from the local source, two currents of same magnitude but opposite phase, and, therefore, not to be affected by the local transmitting equipment, but to receive maximum effect of the distant transmitting equipment; each of said transmitting equipments being in an independent local circuit inductively related to the line; each of said local receiving circuits having transformer-connection with the local transmitting circuit, and its inductive relation to the line comprising an independent transformer-connection; the current in each local receiving circuit, induced through its two said transformer-connections, by the local transmitting circuit, being of opposite phase; and each local receiving circuit also 45 including a loop circuit adjusted in resonance with the frequency of the local transmitting current; and each local transmitting circuit including a loop circuit tuned to resonance with the frequency of the distant 50 transmitting current.

The foregoing specification signed at Washington, District of Columbia, this 29 day of June, 1916.

LOUIS COHEN.
